UNITED STATES PATENT OFFICE

99,254

DESIGN FOR AN AUTOMOBILE FENDER GUARD

John I. Trembot, Chicago, Ill.

Application November 11, 1935, Serial No. 59,477

Term of patent 3½ years

To all whom it may concern:

Be it known that I, John I. Trembot, a citizen of the United States, residing at Chicago, in the county of Cook and State of Illinois, have invented a new, original, and ornamental Design for Automobile Fender Guards, of which the following is a specification, reference being had to the accompanying drawing, forming part thereof.

I claim:

The ornamental design for an automobile fender guard, as shown.

In witness whereof I affix my signature.

JOHN I. TREMBOT.
